UNITED STATES PATENT OFFICE

GEORGE E. COTTRELL, OF DES MOINES, IOWA, ASSIGNOR TO ROLLINS HOSIERY MILLS, OF DES MOINES, IOWA, A CORPORATION OF IOWA

METHOD OF FORMING PICOT EDGES IN STOCKINGS

Application filed December 15, 1930. Serial No. 502,474.

The object of my invention is to provide a method whereby an ornamental picot edge may be formed at the top of so-called full fashioned stockings by automatic machinery without any hand work, and in such manner that the upstanding loops forming the picot edge will all be of uniform height, presenting an attractive and ornamental appearance; and

10 Further in this connection to provide a method by which this desired result may be produced inexpensively.

My invention consists in the arrangement and combination of the various steps of the 15 method by which the objects contemplated are attained, as hereinafter more fully set forth, pointed out in my claim, and illustrated in the accompanying drawings, in which:

20 Figure 1 shows a perspective view of the upper or welt portion of a full fashioned stocking, having a portion of the upper edge thereof illustrating the picot edge.

Figure 2 shows an enlarged sectional view 25 on the line 2—2 of Figure 1.

Figure 3 shows an enlarged detail side elevation of a portion of the upper edge of the stocking illustrating the picot edge; and

Figure 4 shows a portion of the knitted 30 fabric laid out flat and illustrating the tucked stitches in alternate rows formed therein to produce the picot edge when folded along the central line through the tucked stitches.

In practicing my improved method I form 35 the welt portion on a circular knitting machine in the form of an inturned hem. During the first part of this knitting process, one edge of the welt is held stationary on transferring jacks, while the knitting of the 40 welt is completed by a set of needles, and during this knitting process the welt is made in the form of an inturned hem, and then the free edge of the inner welt member 10 is knitted to the outer welt member 11, leaving 45 a portion of the outer welt member projecting below the lower edge of the inner welt member, as illustrated in Figure 2 at 12.

During the above described knitting process, I so arrange the needles of the circular 50 knitting machine that when the central por-

tion of this web member is being knit, the needles will form a tucked stitch on each alternate wale. These tucked stitches are formed along a plurality of courses, preferably three, along a central line between the inner and outer welt members. In forming these tucked stitches the knitting machine is operated as follows:

On the first course of the tucked stitches, one course of stitches is knitted on each alternate needle, and in the second course of stitches one course is knitted on every needle, and in the third course of stitches one course is knitted on every other needle, and at the same time jacks radially and horizontally disposed in line with the inactive needles are brought into position to make loops at the knitting point, and these loops are held on said jacks until the welt fabric is completed. These jacks are then moved to position where each alternate needle will pass through the loops held by the jacks, and the jacks then removed, thus completing the welt.

When the welt portion is completed, it may be transferred to a flat knitting machine, and the stocking is completed on a flat knitting machine to form a full fashioned stocking in the ordinary manner.

I am aware that heretofore picot edges have been formed on stockings by the use of 80 tucked stitches, but this has heretofore been done on a flat knit fabric and then the fabric is folded over by hand along the central line of row of tucked stitches, which is a very delicate operation and requires a great deal 85 of time and skill and substantially adds to the expense of the completed stocking, whereas with my improved method, I have demonstrated in practice that the welt portion will, during the ordinary course of handling and packing the stocking for shipment, become accurately folded along the central line of the tucked stitches, and will produce a completed stocking in which all of the loops between the tucked stitches will be 90 of equal length and will stand straight up, and the tucked stitches will form depressions between these upstanding loops, presenting to the eye the appearance of a perfect picot 95 edge.

I have demonstrated in practice that these stockings with the picot edge made by my improved method may be completed without any appreciable added expense above that ordinarily required for producing similar stockings having plain upper edges.

I claim as my invention:

The method of automatically forming a picot edge on non-rib stockings, which consists of first knitting the welt portion of the stocking on a circular knitting machine in the form of an inturned hem, and during the knitting of the central portion of the in-turned hem forming tucked stitches on spaced apart wales along a number of courses, and finally automatically during the said machine operation knitting the lower edge of the inner welt member to the outer welt member along a line which brings the exact central line of the tucked stitches to the top edge of the stocking.

Des Moines, Iowa, December 6, 1930.

GEORGE E. COTTRELL.
